(57) CLAIM

The ornamental design for a shelf organizer as shown and described.

DESCRIPTION

FIG. 1 is a top perspective view of a shelf organizer showing my new design;

FIG. 2 is a bottom perspective view thereof;

FIG. 3 is a perspective view of one side panel of the shelf organizer;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is an enlarged view of an indicated portion of FIG. 3;

FIG. 11 is a top perspective view of one board of the shelf organizer;

FIG. 12 is a bottom perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is an enlarged view of an indicated portion of FIG. 12;

FIG. 20 is an enlarged view of an indicated portion of FIG. 18; and,

FIG. 21 is a bottom perspective view showing the shelf organizer with foot pads.

The broken lines in FIGS. 1-21 are for the purpose of illustrating portions of the shelf organizer that form no part of the claimed design. The broken lines of the foot pads in FIG. 21 illustrate unclaimed environment and forms no part of the claimed design. The dot-dash broken lines in FIGS. 1-4, 6-7, 10, 12 and 18-21 represent unclaimed boundary lines and form no part of the claimed design. The dot-dot-
